UNITED STATES PATENT OFFICE.

WILLIAM BURT BRODERICK, OF CLEVELAND, OHIO.

DESIGN FOR A FIRE-KINDLER.

SPECIFICATION forming part of Design No. 28,404, dated March 22, 1898.

Application filed January 20, 1898. Serial No. 667,349. Term of patent 14 years.

To all whom it may concern:

Be it known that I, WILLIAM BURT BRODERICK, a citizen of the United States, residing at Cleveland, in the county of Cuyahoga and State of Ohio, have invented and produced a certain new and original Design for a Fire-Kindler; and I do declare the following to be a full, clear, and exact description of the invention, such as will enable others skilled in the art to which it appertains to make and use the same.

My invention relates to a design for a fire-kindler.

The design consists of the configuration of the fire-kindler, as illustrated in the accompanying drawings, in which the same reference characters indicate the same parts of the invention.

Figure 1 is a perspective view of a fire-kindler embodying my design, and Fig. 2 is a transverse vertical section of the same.

The leading features of my design appear in the following description:

1 denotes the convex bottom, terminating in an upwardly-flaring circumferential lip 2. 25

3 represents the foraminous cylindrical wall, and 4 denotes the arch-shaped bail, formed with a central depending eye 5, by which the kindler is manipulated.

The kindler is first filled with ashes or similar refuse material, which is then saturated with coal-oil, and it is then placed under the grate of coal-stoves and on the grate of wood-stoves and the oil ignited.

Having thus fully described my invention, 35 what I claim, and desire to secure by Letters Patent, is--

The design for a fire-kindler, substantially as herein shown and described.

In testimony whereof I have hereunto set 40 my hand in presence of two subscribing witnesses.

WILLIAM BURT BRODERICK.
